(57) **CLAIM**

The ornamental design for a flying disc, as shown and described.

DESCRIPTION

FIG. 1 is a perspective top view of the flying disc.

FIG. 2 is a top view of the flying disc.

FIG. 3 is a front view of the flying disc.

FIG. 4 is a rear view of the flying disc.

FIG. 5 is a bottom perspective view of the flying disc; and,

FIG. 6 is a bottom view of the flying disc.

The broken line showing of indicia in FIGS. 1 through 5 is included for the purpose of illustrating portions of the flying disc which form no part of the claimed design.
